ANTENNA SYSTEM

Lee R. Dobler and Lloyd J. Money,
United States Navy

Application August 9, 1945, Serial No. 609,906

5 Claims. (Cl. 250—33.65)

(Granted under the act of March 3, 1883, as
amended April 30, 1928; 370 O. G. 757)

1

This invention relates in general to multi-purpose antenna systems and in particular to parasitic elements therefor.

In radio and the allied arts it frequently is desirable to provide a multi-purpose antenna system in which a number of antenna arrays having distinct functions are contained on a common frame or support. In such cases a first array may act as an obstruction to a second array whereby reactive loading of one or more of the radiating elements of the second array may result. In this case optimum impedance match between the transmission line and the radiating elements of the second array, especially when an extended frequency range is to be covered by the second array, is unobtainable.

It is an object of this invention to provide, in an antenna system in which at least one of the radiating elements is reactively loaded by an obstruction, a means for obviating the effects of such reactive loading.

Another object of this invention is to provide a means for obviating reactive loading of a radiating element by an interfering element or surface placed in proximity thereto and thereby maintaining the free space radiation pattern of the radiating element.

Another object of this invention is to provide an antenna system which carries a number of functionally distinct antenna arrays on a common antenna frame.

Other objects and features of the present invention will become apparent upon a careful consideration of the accompanying drawings and the detailed discussion which follows:

Fig. 1 shows an end-view of an antenna system embodying the principles of the principal invention, and

Fig. 2 shows a "front" view taken from the direction of maximum radiation by the antenna system of Fig. 1.

A dual purpose antenna system constructed according to the teachings of this invention is shown in Figs. 1 and 2. In particular the antenna system of the drawing comprises two functionally distinct arrays. The first is a radar antenna designed to produce a pair of divergent but slightly overlapping beam patterns and comprises, in part, two cylindrical parabolic reflecting surfaces held in juxtaposed relationship by a pair of end plates

2

20 and 21 welded to each end of the parabolas 10 and 11. Each of the parabolas is made, for example, from perforated sheet metal and they are so oriented with respect to one another that their axes are slightly divergent to thereby provide divergent beam patterns. At the focal line of each of the parabolic sections 10, 11 are a number of horizontal half-wavelength radiating elements 13 located approximately a wavelength apart, center to center. The manner in which the radiating elements 13 are supported at the focal lines of the respective parabolas and their mode of excitation being in accordance with the teaching of the prior art. With this arrangement it was found that excessive energy was present in side lobes of the radiation pattern. It was further found that these side lobes could be effectively suppressed by the incorporation of a sub-antenna assembly comprising a third smaller cylindrical parabolic reflecting surface 12 with a pair of half wave radiating elements 13—A similarly supported and excited at its focal line. Each end of the parabola 12 is secured to a yoke member 16, shown partly cut-away in Fig. 1. The parabola 12 is then positioned in front of the center of the main reflectors 10, 11 by the attachment of the yokes 16 to a retaining member 18 fixed at the intersection of parabolas 10, 11. Also supporting parabola 12 and providing a path for energy to the radiating elements 13—A is a coaxial tubing, the rigid outer conductor of which is shown at 17. The coaxial line 17 is mounted at the center point of the antenna assembly and extends through the screens 10, 11 at their line of intersection to the main transmission line, not shown. The exact position and size of the reflector 12 and its elements 13—A, as well as the amount and phasing of the energy applied to elements 13—A are critical for optimum side lobe suppression but are not within the scope of this invention.

The second array comprises a pair of half-wavelength vertical end radiators 14 and a centrally disposed radiator 14—A. This array is designed to provide a vertically polarized radiation pattern at a lower frequency than the first array and is arranged to function, for example, in connection with an "identification system," of any suitable type known to the art and whose function is to determine whether an object seen by the radar is friendly or unfriendly. For dependable

operation of the "identification system" it is of utmost importance to positively establish the fact that the object being challenged by the system is the same as that at which the radar antenna is directed. This means that at least three half-wavelength spaced dipoles 14 and 14-A are required in order to obtain the desired directivity in the "identification system" antenna beam pattern. To facilitate feeding the elements and prevent objectionable back radiation it is found desirable to mount the radiating elements 14, 14-A upon the line of intersection 18 of the parabolas 10, 11, and supply energy to them by a suitable transmission means, not shown, fed through openings in the reflector screen. In the preferred case the one half-wavelength dipoles 14 and 14-A are current fed so as to produce a voltage minimum at these center points permitting a rigid conductive connection by welding or clamping the dipole center points to the intersection of the parabolas 10 and 11.

It is apparent that in the last antenna assembly it is not possible to provide a symmetrical array comprising at least three radiating elements in the vertical set 14, 14-A without locating one of the elements in proximity to the lobe suppressing reflector 12. The presence of this obstruction does not adversely affect the radiation field patterns of the combination of the elements 14, but it does produce reactive loading on the partially covered element 14-A. By proper impedance matching of the radiating element to the line feeding it, satisfactory operation with a standing wave ratio of E minimum to E maximum in the transmission line greater than 0.5 is possible at a particular frequency.

Normally the identification equipment employing the radiators 14, 14-A must function over an extended frequency range, therefore these elements are constructed of large diameter tubing to give the broadband characteristics. The reactive loading placed upon element 14-A by the reflector 12 causes that element to be sharply resonant so that operation over an extended frequency range is not possible.

It was found that this reactive loading could be reduced substantially by interposing a parasitic element 15 tuned to approximately the same wavelength as radiator 14-A between the reflector 12 and the element 14-A. The parasitic element 15 is mounted, clamped, for example to the outer conductor 17 of the coaxial tubing feeding elements 13-A. Element 15 is not excited directly but is a true parasite inasmuch as it receives its excitation from element 14-A. The insertion of the parasite 15 produces two resonant points in the frequency response characteristics of the central element 14-A with little mis-tuning occurring between. The spacing of these resonant points is a function of the diameter of the radiator 14-A and that of the parasitic element 15, being less where smaller diameter elements are employed. The spacing of the parasite 15 from radiator 14-A and from the back surface of reflector 12 are both of importance but are best determined empirically. In the typical case here chosen, the spacing between the parasite 15 and the radiator 14-A is approximately 8% of the average wavelength. Also in this typical case the length of the end radiators 14 is approximately 48% of the average wavelength. The length of the center radiator 14-A is approximately 45% of the average wavelength, while the parasite 15 is slightly shorter (or tuned to a higher frequency) than the center radiator 14-A.

A. Under these conditions it is possible to obtain satisfactory operation without retuning over a frequency range as great as 10% of the average frequency.

5 The exact action of the parasitic element 15 in reducing reactive loading of radiator 14-A is not known, however, it is believed that the radiator 14-A and the parasite 15 function as over-coupled tuned circuits producing the familiar dual-peaked frequency response.

10 The addition of the parasitic element 15 and the vertical radiators 14, 14-A does not materially affect the operation of the first antenna array since the respective planes of polarization 15 bear 90 degree relationships to each other.

15 From the foregoing discussion it is apparent that the principles of this invention may be applied to other types of antenna systems where reactive loading of one or more elements is produced as a result of the proximity of an interfering surface. It would also be applicable where flat rather than parabolic reflecting surfaces are employed for the antennas 13, 13-A.

20 The invention described herein may be manufactured and used by or for the Government of the United States of America for governmental purposes without the payment of any royalties thereon or therefor.

25 What is claimed is:

30 1. In an antenna system having first and second arrays positioned on a common antenna frame such that the first array forms an obstruction to at least one radiating element of the second array whereby reactive loading of said radiating element results, a parasitic element positioned intermediate said radiating element and said first array, said parasitic element being tuned to substantially the same frequency as said radiating element.

35 2. In an antenna system having first and second arrays positioned on a common antenna frame such that the first array forms an obstruction to at least one radiating element of the second array whereby reactive loading of said radiating element results, a parasitic element positioned intermediate said radiating element and said first array, said parasitic element being tuned to substantially the same frequency as said radiating element.

40 3. In an antenna system having first and second arrays positioned on a common antenna frame such that the first array forms an obstruction to at least one radiating element of the second array whereby reactive loading of said radiating element results, a parasitic element positioned intermediate said radiating element and said first array at a fraction of a wavelength from said radiating element, said parasitic element being tuned to substantially the same frequency as said radiating element.

45 4. In an antenna system having first and second arrays positioned on a common antenna frame such that the first array forms an obstruction to at least one radiating element of the second array whereby reactive loading of said radiating element results, a parasitic element positioned intermediate said radiating element and said first array at a fraction of a wavelength from said radiating element, said parasitic element being tuned to a frequency slightly higher than said radiating element.

50 5. An antenna system comprising, a first antenna assembly having a reflector and associated array of radiating elements, a second antenna assembly having a reflector and associated array of radiating elements, said second assembly being positioned to the radiation side of said first assembly, a third and functionally distinct array of radiating elements, said third array positioned 55 intermediate said first and second antenna assemblies and a parasitic element positioned intermediate said third array and said second assembly, said parasitic element being tuned to substantially the same frequency as the radiating elements of said third array.

5. An antenna system comprising, a first antenna assembly having a reflector and associated array of radiating elements, a second antenna assembly having a reflector and associated array of radiating elements, said second assembly being positioned to the radiation side of said first assembly, a third and functionally distinct array of radiating elements, said third array positioned intermediate said first and second antenna assemblies, and a parasitic element positioned intermediate said third array and said second assembly at a fraction of a wavelength from said third array, said parasitic element being tuned to substantially the same frequency as the radiating elements of said third array.
